(57) **CLAIM**

The ornamental design for a mounting assembly for a weight rack, as shown and described.

DESCRIPTION

FIG. 1 is a top, front, right perspective view of a mounting assembly for a weight rack, showing our new design in an extended position;

FIG. 2 is a front view thereof;

FIG. 3 is a left view thereof;

FIG. 4 is a right side view thereof;

FIG. 5 is a top view thereof;

FIG. 6 is a bottom view thereof;

FIG. 7 is a top, front, right perspective view showing our new design of FIGS. 1-6 in its exemplary environment, with the exemplary environment shown in an extended position; and,

FIG. 8 is a top, front, right perspective view showing our new design of FIGS. 1-6 in its exemplary environment, with the mounting assembly for a weight rack and the exemplary environment shown in a folded position.

The broken lines immediately adjacent to the shaded area define the bounds of the claimed design and form no part thereof. The broken lines depicting the remainder of the mounting assembly for a weight rack show features that form no part of the claimed design.
